UNITED STATES PATENT OFFICE.

BLANCHARD CHAMBERLAIN, OF BELLEFONTAINE, OHIO.

SURGICAL TRUSS.

SPECIFICATION forming part of Letters Patent No. 724,808, dated April 7, 1903.

Application filed June 17, 1902. Serial No. 112,072. (No model.)

To all whom it may concern:

Be it known that I, BLANCHARD CHAMBERLAIN, a citizen of the United States, residing at Bellefontaine, in the county of Logan and State of Ohio, have invented certain new and useful Improvements in Surgical Trusses; and I do hereby declare the following to be a full, clear, and exact description of the invention, such as will enable others skilled in the art to which it appertains to make and use the same.

My invention relates to improvements in trusses for the treatment of hernia or like injuries; and it consists of certain novel features, that will be hereinafter described and claimed.

Reference is had to the accompanying drawings, in which the same parts are indicated by the same letters throughout the several views.

Figure 1 is a perspective view of the improved truss. Fig. 2 is a rear elevation of the back pad. Fig. 3 shows a section along the line 3' 3' of Fig. 2. Fig. 4 shows a section along the line 4' 4' of Fig. 1, and Fig. 5 is a detail showing one of the rubber caps removed.

A represents a resilient loop made, preferably, of spring-steel, nickel-plated, and screw-threaded at a^0 . The end A' of this loop is bent, as at a' , and passes through a hole b' in the stud B' at the rear of the back pad B. This pad is thus swiveled onto the loop A. The fork A² is adjustably connected, as by screwing, on the screw-threads a^0 . The end a^2 of said fork is sprung into recesses c² in the stud C' at the back of the front pad C. This pad C is concaved, as indicated in Fig. 4, while the pad B may be either flat or may be specially made of the shape of that portion of the back of the wearer to which it is to be applied.

Over the pads B and C, I place a cap D, preferably of rubber; but it may be made wholly or any part of buckskin or other soft material. I prefer rubber, however, especially for the pad C. These pads B and C are preferably made of aluminium not only on account of lightness, but also because this

metal does not corrode under the influence of 50 excretions from the skin or of the sulfur-gases which discharge from the human body.

By having the pad C cup-shaped, as shown, it tends to close the rupture instead of spreading the walls of the same, as happens when a 55 convex pad is applied. Furthermore, by having an air-tight elastic cap over this cup-shaped pad the air is imprisoned and forms a soft yielding cushion to the injured part. Moreover, by having a pad of this character 60 the cap may be readily removed when washed or a fresh one substituted when desired, while the whole truss itself may be thoroughly cleansed at any time. It will be seen that this truss is readily applied, occupies a very 65 small space, and hence will not be apparent below the clothing of the wearer, but may be readily adjusted to fit the individual wearer. These and the various other advantages over the trusses now in use will readily suggest 70 themselves to any truss-maker or any one who has been so unfortunate as to be obliged to wear a truss.

Having thus described my invention, what I claim, and desire to secure by Letters Patent 75 of the United States, is—

1. A truss comprising a loop of resilient material bent over at one end and screw-threaded at the other, with a pad having a stem perforated to receive said bent-over end 80 and revolubly connected thereto, a combined nut and fork adapted to screw over the other end of said loop, and a pad swiveled to said fork, substantially as described.

2. A truss comprising a loop of resilient 85 material, having a pad swiveled to one end thereof, a combined nut and fork adapted to screw over the other end of said loop, and a pad swiveled to said fork.

3. A truss comprising a loop of resilient 90 material bent over at one end and screw-threaded at the other, with an aluminium pad having a stem perforated to receive said bent-over end, and revolubly connected thereto, a combined nut and fork adapted to screw 95 over the other end of said loop, an aluminium pad swiveled to said fork, and rubber caps adapted to slip over said aluminium pads,

substantially as and for the purpose described.

4. A truss comprising a loop of resilient material having an aluminium pad swiveled

5 to one end thereof, with screw-threads on the other end, a combined nut and fork adapted to screw over the said screw-threads, an aluminium pad swiveled to said fork, and rub-

ber caps adapted to slip over said pads, substantially as and for the purpose described. 10

In testimony whereof I affix my signature in presence of two witnesses.

BLANCHARD CHAMBERLAIN.
